UNITED STATES PATENT OFFICE.

CHARLES W. BECK, OF DETROIT, MICHIGAN, ASSIGNOR TO THE BECK-FROST CORPORATION, OF DETROIT, MICHIGAN, A CORPORATION OF MICHIGAN.

HOLDER FOR OIL-CANS OR THE LIKE.

1,297,435.

Specification of Letters Patent. Patented Mar. 18, 1919.

Application filed July 12, 1915. Serial No. 39,467.

To all whom it may concern:

Be it known that I, CHARLES W. BECK, a citizen of the United States of America, residing at Detroit, in the county of Wayne 5 and State of Michigan, have invented certain new and useful Improvements in Holders for Oil-Cans or the like, of which the following is a specification, reference being had therein to the accompanying drawings.

My invention relates to holders for oil cans or the like and resides in the provision of a simple construction of holder that may be easily and cheaply manufactured; in 15 the provision of a holder that will readily adapt itself to the can and which is so constructed as to firmly hold the bearings and the holder in contact, so as to prevent rattling. Further, in the provision of a simple 20 construction of holder by which the can will be retained against accidental displacement.

The invention consists in the peculiar construction, arrangement and combination of parts as hereinafter set forth and particularly pointed out in the claims.

In the drawings,—

Figure 1 is a perspective view of the holder embodying the invention;

Fig. 2 is a side elevation showing the oil 30 can in engagement with the holder; and

Fig. 3 illustrates a modification.

Referring to the construction shown in Figs. 1 and 2 of the drawings, A designates an attaching section in the form of an angle 35 plate, the vertical flange B of which is adapted to be secured to a suitable support, the flange B having apertures C for receiving securing screws or the like. Carried by the laterally-extending flange D of the plate 40 A is a supporting section E in the form of a wide, flat plate having its inner end resting upon the flange D and pivoted thereto adjacent one side, as indicated at F. G and H are lugs struck out of the flange D and 45 the member E respectively, and I is a spring having its opposite ends connected to the lugs G and H. This spring acts to normally hold the rear edge J of the plate E against the inner face K of the plate B, but will permit the section E to be swung upon the pivot 50 A as shown in Fig. 1.

L is a retaining projection or lug struck out of the plate B and projecting outwardly from the inner face thereof. At the outer 55 end of the plate E is a retaining section

preferably comprising spaced lugs M and N turned up at the end of the plate E. The lugs L, M and N are so shaped and so proportioned as to engage over the flared portion O at the base of the can P, as shown 60 in Fig. 2. When the can is in engagement with the holder it is arranged as shown in Fig. 2. In this position the spring I acts to yieldably draw the lugs M and N toward the lug L, since the plate E is pivoted adjacent 65 one side thereof. Since the lower portion Q of the lug L is somewhat rounding, when it is desired to remove the can from the holder it is merely necessary to lift the can upwardly and the rounding portion Q will effect a gradual rocking of the member E about its pivot F, thereby moving the lugs M and N away from the lug L and allowing the can to be withdrawn. To engage the can its edge is first engaged with 70 the lugs M and N and then the can moved downward into engagement with the lug L. Since the latter is rounding, it will cause a rocking of the member E upon its pivot until the edge of the can has passed below 75 the lug L. The spring I will then tend to return the plate E, which will cause the lugs M, N and L to be resiliently held in engagement with the can. As will be readily apparent, the spring I will take up any 80 play between the lugs and the can, thereby preventing rattling.

In the construction shown in Fig. 3, the holder has a vertical attaching section A' and a supporting section B' formed integral 90 with and extending laterally from the section A', both of these sections being made from a comparatively wide, flat strip of sheet metal. Extending outwardly from the inner face of the plate A' is a resilient 95 retaining lug C' in the form of a spring finger. D' E' are retaining lugs turned up from the end of the plate B' and adapted to engage over the lower edge of the can. The can is engaged with the support by engaging its edge with the lugs D' E' and then forcing the can downwardly against the tension of the spring finger C'. In order to hold the periphery of the can in tight contact with the lugs, the plate B' is provided 100 with a spring finger F' struck thereout of, which contacts with the bottom of the can and tends to raise the latter. The tension of the member F' however, is not sufficient 105 to move the can out of engagement with the 110

bearings against the pressure of the finger C'.

In each of the constructions described, the support not only is provided with suitable retaining lugs for engaging the can, but also the holder is provided with resilient means for taking up any play between the lugs and the periphery of the can, so as to prevent rattling.

10 What I claim as my invention is:

1. A holder for cans or the like, comprising a vertically-arranged attaching plate, a laterally-extending supporting plate, there being a resilient lug struck out from the attaching plate, retaining means at the outer end of the supporting plate, and a spring-pressed member carried by the supporting plate for engaging the bottom of the can.

15 2. A holder for cans or the like, comprising a vertically-arranged attaching plate, a

laterally-extending supporting plate, there being a resilient lug struck out from the attaching plate, retaining means at the outer end of the supporting plate, and a spring-pressed member carried by one of said plates 25 for engaging the bottom of the can.

3. The combination with a vertically-arranged attaching plate, of a laterally-extending supporting plate, coöperating retaining lugs upon said plate and engaging the periphery of the can, and a spring-pressed finger carried by one of said plates for engaging the bottom of the can, for the purpose described.

30 In testimony whereof I affix my signature in presence of two witnesses.

CHARLES W. BECK.
